CLAIM

The design for a photographic display apparatus, as shown.

DESCRIPTION

FIG. 1 is a top plan view of a photographic display apparatus in the closed position showing my new design;

FIG. 2 is a back view of the apparatus in the closed position;

FIG. 3 is a top view of the apparatus in the closed position;

FIG. 4 is a bottom view of the apparatus in the closed position;

FIG. 5 is a view of the left side, of the apparatus, in the closed position;

FIG. 6 is a view of the right side, of the apparatus, in the closed position;

FIG. 7 is a plan view of the apparatus in the open position;

FIG. 8 is a back view of the apparatus in the open position;

FIG. 9 is a top view of the apparatus in the open position;

FIG. 10 is a bottom view of the apparatus in the open position;

FIG. 11 is a view of the left side of the apparatus in the open position; and

FIG. 12 is a view of the right side of the apparatus in the open position.

FIG. 1.

FIG. 6.

FIG. 4.

FIG. 3.

FIG. 2.

FIG. 5.
